Ina T. Dwyer
Design for Butler Cook Stove

Patented Dec. 23, 1886

Des. 857

John T. Davy, of Troy, N.Y.
Letters Patent No. 857, Dated Dec. 23rd 1836

The Schedule referred to in these Letters Patent and making part of the same.

To all whom it may concern:

Be it known that I, Jno. T. Davy of Troy in the county of Rensselaer and State of New York, have invented, or produced, a new and original design for a parlor cook stove. Which I call the "Patriot," and I do hereby declare that the following is a full, clear and exact description of the same, reference being had to the annexed perspective drawings making part of this specification, in which Fig. 1 is a view of the stove, and Fig. 2 is a view of the ornamental top of the stove.

The description of my parlor cook stove design, is as follows, viz: A is the top plate, with ornamental moulding (a). B is the front plate, having the scrolls (B B) at the top, and side ornaments (C C): the lower part of the plate forms an arched recess, having an ornamental arch (d d d). C C. are the front fire doors decorated with the checkered panels (e e), and borders formed of the scrolls (f f) and shells (g g). D is the oven door having the center ornament (h), leaves and scrolls (i, j) shell work (k) checkered surface (l). E is the end plate, with the ornamental work (m) at the top. F is the fire door, with centre ornament (n) scrolls (o), and shell border (p), checkered surface (q). A is a raised panel, with the surface decorated in the same style as the fire door F, H is the bottom plate, with the ornamental moulding (r, s) and (t, u). I is the damper plate, J is the leg ornamented with the leaf (t) and scrolls (u). K (Fig 2) is the ornamental top plate, composed of the scrolls (v, w), center piece (w) top ornament (x) and shell work (y).

Having fully described my design for a parlor cook stove, what I claim as new therein and desire to secure by letters patent is: the ornamental design and configuration of parlor cook stove plates, such as herein described and shown in the annexed drawings.

Witnesses.
